UNITED STATES PATENT OFFICE.

JOSEPH A. MOHRHAUSER, OF MADISON, WISCONSIN.

TOILET-SEAT COVER AND SUPPORT.

1,187,643.

Specification of Letters Patent. Patented June 20, 1916.

Application filed March 26, 1915. Serial No. 17,226.

To all whom it may concern:

Be it known that I, JOSEPH A. MOHRHAUSER, a citizen of the United States, residing at Madison, in the county of Dane and State of Wisconsin, have invented certain new and useful Improvements in Toilet-Seat Covers and Supports, of which the following is a specification.

This invention contemplates an improved 10 toilet seat cover and support therefor and has as its primary object to provide an arrangement whereby one of the covers may be employed each time the seat is used and wherein, a supply of covers will be supported adjacent the seat in such manner that 15 one of the covers may be readily moved into proper position when it is desired to use the seat.

The invention has as a further object to 20 provide a support for the covers adapted to receive a relatively large supply of covers, and of such character that the said covers may be readily moved thereon, one at a time, into operative position.

25 A further object of my invention is to provide a support for the covers adapted to coact with the toilet seat to properly guide the covers into operative position and so arranged as to hold the covers in place upon 30 the seat.

The invention has as a still further object to provide a support for the covers which may be readily disassembled to receive a new supply of covers, and wherein the accidental 35 displacement of the covers from the support will be reduced to a minimum. And a still further object of the invention is to provide an improved cover adapted to overlie the upper area of the seat to thus 40 provide a sanitary and efficient protection for the user of the seat but which will, nevertheless, be of exceedingly simple construction and consequently furnish an inexpensive article.

45 Other and incidental objects will appear as the description proceeds and in the drawings wherein I have illustrated the preferred embodiment of my invention and wherein similar reference characters designate corresponding parts throughout the several views, Figure 1 is a front elevation showing a supply of my improved covers supported adjacent the toilet seat, Fig. 2 is a side elevation more particularly showing the construction 50 and arrangement of the support for the covers, Fig. 3 is a detail perspective view of

one of the covers, Fig. 4 is a fragmentary sectional view showing the mounting of the support carried by the retaining rod for the covers, Fig. 5 is a fragmentary perspective 60 view showing the connection between the sections of each of the cover supporting rods.

In carrying out my invention, I employ a seat cover 10 which is preferably formed of paper, although as will be clear, any 65 other suitable material may be used, and which, in general outline, is the shape of an ordinary toilet seat. Medially formed in the cover 10 is an opening 11 also similar in outline to the opening of an ordinary toilet 70 seat.

75 Formed on the rear edge of the cover 10 are spaced laterally extending lugs 12 upon one side of which are secured reinforcing tabs 13, the said tabs and lugs being provided with alined openings 14. Formed on the forward edge of the cover 10 is a laterally projecting lug 15 similar to the lugs 12, which is also provided with a reinforcing tab 16 the tab 16 and lug 15 being provided 80 with alined openings 17. It will be observed that the lug 15 and tab 16 are arranged in a plane midway between the lugs 12.

85 In Figs. 1 and 2 of the drawings, I have shown the manner in which the covers 10 are supported adjacent a closet bowl, the closet bowl being conventionally shown at 18 and being arranged adjacent a wall 19, the said bowl being provided with a seat 20.

90 Mounted upon the wall 19 and arranged medially of the seat 20 are spaced L-shaped supporting rods 21. Each of the rods 21 is formed of sections 22 and 23 respectively, the adjacent terminals of which, as best shown in Fig. 5 of the drawings, are screw 95 threaded and are detachably connected by a sleeve 24. The inner terminals of the sections 22 of each of said rods are provided with an attaching plate 25, adapted to seat against the adjacent face of the wall 19 to 100 be connected thereto in any suitable manner, the sections 22 of said rods extending laterally from the wall with the sections 23 thereof, depending toward the seat 20 and abutting against the rear edge of the said seat at their free ends. As best shown in Fig. 2 of the drawings, the vertically arranged sections 23 of the rods are equally spaced upon each side of the longitudinal medial line of the seat.

110 Mounted upon the wall 19 in spaced relation to the supporting rods 21 and arranged

in a plane medially thereof is a retaining rod 26 which extends laterally from the wall and which is provided, at one extremity, with an attaching plate 27 adapted to seat 5 against the adjacent face of the wall to be suitably connected thereto. The outer extremity of the rod 26 terminates in substantial alinement with the vertically arranged portions of the supporting rods 21 and upon 10 one side, is provided with a longitudinally extending recess 28 best shown in Fig. 4 of the drawings. Connected at one extremity to the rod 26 at the inner end of said recess, is a flat spring 29, the free extremity of 15 which normally projects laterally above the upper side of the adjacent extremity of the rod and is adapted to be depressed within the recess 28, the spring providing a stop member.

20 In use, a number of the covers 10 are mounted in position upon the supporting rods 21 and the retaining rod 26, as shown in Fig. 2 of the drawings. For this purpose, the sections 23 of each of said rods are 25 removed and the sections 22 of the rods threaded through the openings 14 of the lugs 12 and reinforcing tabs 13 of the covers, it being understood that the rods 21 are spaced apart a distance equal to the distance between 30 said openings. At the same time, the retaining rod is threaded through the openings 17 formed in the lugs 15 and reinforcing tabs 16 of the covers, it being understood, of course, that the spring 28 is depressed within the recess 27 to permit the tabs to slide freely over the outer end of the retaining rod. When thus arranged in place, the sections 23 of the supporting rods are disposed in position and the covers are 35 then ready for use. The spring 28 of the retaining rod is compressed within the recess 27 and the free end of one of the covers is then removed from the retaining rod, the lugs 12 of the cover being, at the same time, 40 moved longitudinally upon the supporting rods toward the vertically arranged portions thereof. The cover is then moved to position over the seat 20 as shown in Fig. 2 of the drawings, being guided to such position 45 by the sections 23 of the supporting rods, and it will be observed that the supporting rods are adapted to effectually hold the cover in place during use. When used, the cover may be readily torn from the supporting rod by a slight pull thereon.

50 It will thus be seen that a separate cover may be employed each time the seat is used, while the covers will be conveniently accessible. Furthermore, it will be seen that I 55 provide an arrangement wherein a new supply of covers may be readily arranged in position upon the supports therefor when necessary and that the spring 28 of the retaining rod will normally prevent the accidental displacement of the covers.

Having thus described my invention, what I claim and desire to secure by Letters Patent is—

1. The combination with a toilet seat, of spaced L-shaped retaining rods mounted adjacent the seat and abutting the seat at their free ends, the said rods being formed in sections detachably connected, and a retaining rod mounted in spaced relation to said supporting rods, the said supporting rods 75 being adapted to receive a seat cover movable thereon from inoperative position in engagement with said retaining rod to operative position upon the seat.

2. The combination with a toilet seat, of spaced supporting rods mounted adjacent the seat, a retaining rod arranged in spaced relation to said supporting rods, and a stop member carried by the free end of said retaining rod and yieldably urged to project 85 laterally upon one side thereof, said supporting rods being adapted to receive a seat cover movable thereon from inoperative position in engagement with the retaining rod upon one side of said stop member to 90 operative position upon the seat.

3. A device of the character described including a supporting rod having angularly disposed portions, and a retaining rod, the supporting rod being mounted by one of 95 its said portions adjacent a toilet seat with the other of its said portions adapted to abut one edge of the seat for limiting the movement of the free end of the said supporting rod toward the seat and the retaining rod being mounted adjacent the supporting rod to extend toward the seat and being adapted to detachably engage a seat cover carried by the supporting rod and movable thereon from inoperative position 100 to operative position upon the seat.

4. A device of the character described including a supporting rod, and a retaining rod, the supporting rod being mounted adjacent a toilet seat with its free extremity 110 adapted to abut one edge of the seat for limiting the movement of the free end of the said supporting rod toward the seat and the retaining rod being mounted adjacent the supporting rod to extend toward the seat, the free extremity of the said supporting rod being detachable from the body 115 of the rod whereby a seat cover may be engaged with the supporting rod for movement, from inoperative position thereon in 120 engagement with the retaining rod to operative position upon the seat.

5. A device of the character described including a supporting rod, a retaining rod, the supporting rod being mounted adjacent 125 a toilet seat with one extremity thereof extending toward the seat and the retaining rod being mounted adjacent the supporting rod to extend substantially parallel with the seat, and a yieldable stop member connected 130

at one extremity with the retaining rod and normally projecting at its opposite extremity upon one side of the said rod, the supporting rod being adapted to receive a seat cover movable from inoperative position thereon in engagement with the retaining rod upon one side of said stop member to operative position upon the seat.

6. A device of the character described including a supporting rod, a retaining rod provided with a recess, the supporting rod being mounted adjacent a toilet seat and having one extremity thereof extending toward the seat and the retaining rod being mounted adjacent the supporting rod and extending substantially parallel to the seat, and a yieldable stop member carried by the

retaining rod and normally projecting at its free extremity upon one side thereof, the supporting rod being adapted to receive a seat cover movable thereon from inoperative position in engagement with the retaining rod upon one side of said stop member to operative position upon the seat, the said stop member being movable at its free extremity into said recess to free the said cover.

In testimony whereof I affix my signature in presence of two witnesses.
